UNITED STATES PATENT OFFICE.

GEORGE H. BARKER, OF LOS ANGELES, CALIFORNIA, ASSIGNOR TO IMPROVED SANITARY FIXTURE COMPANY, OF LOS ANGELES, CALIFORNIA, A CORPORATION OF CALIFORNIA.

LAVATORY APPLIANCE.

1,122,463.

Specification of Letters Patent. Patented Dec. 29, 1914.

Application filed November 10, 1913. Serial No. 200,015.

To all whom it may concern:

Be it known that I, GEORGE H. BARKER, a citizen of the United States, residing at Los Angeles, in the county of Los Angeles and State of California, have invented certain new and useful Improvements in Lavatory Appliances, of which the following is a specification.

My invention relates to lavatory appliances, and has particular reference to a novel combined washstand and bath-tub.

In many instances it has been found desirable in situations where space is limited, to install a combined wash-stand and bath-tub, the stand being superposed on the tub, the same fluid-supply connections being used for both receptacles and both receptacles using the same waste outlet. A further advantage in this construction is in the economy effected in plumbing costs. A particular advantage in the location of the water supply faucet at a point considerably above the plane of the top of the tub is in that the user may, while sitting in the tub, direct fluid on his person or for the purpose of washing the hair.

My invention has for its principal object the provision of a specific form of connection between the tub and superposed wash-basin. It will be understood, of course, that a preferable construction is one in which the wash-basin is superposed at the proper height on the tub, there being an open space between the basin and the tub. This is more sanitary in that it provides for ventilation and permits cleaning as required. When such basin is superposed on standards on the tub the water supply and waste conduits must, in addition, be extended above the tub. This makes a somewhat unsightly construction and is not in every way satisfactory. I have conceived the idea of employing the standards or supports for the basin as the fluid supply conduits, and my invention is broadly for such construction.

The invention will be more readily understood by reference to the accompanying drawings, in which—

Figure 1 is a side elevation of a tub and superposed wash-basin, a portion of the tub and basin being broken away, and Fig. 2 is a plan view.

Referring more particularly to the drawings, it will be seen that I provide a tub 10

of usual construction, having a top flange 11, waste outlet 12, and overflow outlet 13. The waste outlet terminates in a T 14 communicating with a conduit 15, to the upper end of which is connected a T 16 into which the overflow outlet 13 of the tub is directed. Mounted above the tub is a wash-basin 17 having a waste outlet 18 and an overflow outlet 19. The waste and overflow outlets terminate in a T 20 which communicates with a T 16 by tube 21. T 20 rests securely on the flange 11 of the tub, and through the overflow conduit 19 provides a support for one side of the wash-basin 17. Water supply conduits 22 are directed to the appliance, these tubes extending to a point beneath the flange 11 and projecting therethrough into a further hollow standard or tube 23, being securely held by means of a nut 24. These hollow standards 23 are capped by a special angle 25 having an apertured ear 26 extending therefrom. This ear cooperates with an apertured lug 27 integral with the wash-basin 17, a bolt 29 being passed through the apertures to hold the parts in proper relation. A further conduit 29 extends from the angle 25 and terminates in the special faucet 30. The faucet has two outlets 31, 32, the former directing fluid into the wash-basin and the latter into the tub. Suitable valves 33 control the supply of hot and cold fluid, whereas a further valve 34 serves to direct the fluid into either of the receptacles. It will be noted that the tube 21 carrying the waste from the basin 17 is extended down through the T 16 and conduit 15, terminating at a point just below the waste outlet 12 of the tub. This obviates the possibility of waste from the basin running into the tub. By this arrangement, the basin is properly supported, water and waste connections are provided, and the device is made slightly and sanitary.

It will be obvious that the specific arrangement herein shown might be changed, all without departing from the spirit of my invention.

I claim:

1. In a lavatory appliance, the combination of a tub and a superposed wash basin, supports for said basin, one or more of said supports being hollow and acting as conduits for supplying liquid to said basin, substantially as described.

2. In a lavatory appliance, the combination of a tub and a superposed wash-basin, means for supplying hot and cold water to said basin, said basin being supported on the water supply conduits, substantially as described.

3. In a lavatory appliance, the combination of a tub and a superposed wash-basin,

means for supplying liquid to and discharging the same from said basin, said basin being supported on the supply and discharge conduits, substantially as described.

GEORGE H. BARKER.
